(57) **ABSTRACT**

An elastic resistance training apparatus for the performance of ankle plantar flexor resistance exercises, dorsi flexor resistance exercises, ankle inverter resistance exercises, or ankle everter exercises by a user. The apparatus comprises an elastic cord with a primary loop at each end configured to engage the dorsum and plantar surfaces of the user's foot. An auxiliary loop is connected to the primary loop and configured to engage the user's calcaneus bone when the primary loop engages the dorsum and plantar surfaces of the user's foot centering the apparatus at the talocrural joint to enable the user to perform talocrural joint movements without the apparatus disengaging from the user's foot during resistance exercises.

FIG.5

FIG.6

FIG.7

1

ELASTIC TRAINING APPARATUS

BACKGROUND

The present invention relates to the fitness industry, therapeutic rehabilitation industry, and sports performance industry. The embodiments herein relate generally to an elastic resistance training apparatus for the performance of ankle plantar flexor exercises, dorsi flexor exercises, ankle inverter exercises, or ankle everter exercises by a user.

There are countless resistance training devices in the form of elastic resistance bands and elastic resistance tubing devices that are currently on the market. Many of these devices such as U.S. Pat. No. 6,884,202 B2 are attached to the user's body in various arrangements by using cuffs and/or come with removable resistances that can be altered or switched by using clips to allow the user to perform the exercises and or activity that is desired. Another such device, U.S. Pat. No. 7,087,003 B1, provides a device that slips over the toe box of the user's shoe to perform the desired exercise. Although there are many more products that are available in the market for elastic resistance training, many of these devices suffer from the defect of being easily dislodged or disengaged from the user resulting in ineffective workouts.

Resistance exercise tubing and elastic bands are well known for their use in therapeutic rehabilitation and fitness training. These devices are typically applied at the distal femur and/or the distal tibia of both legs to provide resistance training to the hip musculature which includes hip flexors, hip extensors, hip internal rotators, hip external rotators, hip adductors and hip abductors whether it be for therapeutic rehabilitation and/or fitness training. The resistance for many of the products is created by the movement of limbs in opposite directions. This creates tension of the elastic resistance tubing and elastic band.

A recognized problem with the prior art devices is the inadvertent sliding and movement of the devices during use. The prior art devices frequently move up and down the leg or slide off the foot when in use which results in decreased performance and results.

It is an object of the present invention to provide users with a resistance training device that stays in place during multiple forms of exercise and resistance training.

A further object of the present invention is to allow the user the ability to improve fitness in regards to progressive resistance training, flexibility, balance, coordination, muscle endurance and muscle strength.

A further object of the present invention is to provide the user the ability to perform functional movements while using the present invention.

SUMMARY

An elastic resistance training apparatus for the performance of ankle plantar flexor resistance exercises, dorsi flexor resistance exercises, ankle inverter resistance exercises, or ankle everter exercises by a user. The apparatus comprises an elastic cord with a primary loop at each end configured to engage the dorsum and plantar surfaces of the user's foot. An auxiliary loop is connected to the primary loop and configured to engage the user's calcaneus bone when the primary loop engages the dorsum and plantar surfaces of the user's foot centering the apparatus at the talocrural joint to enable the user to perform talocrural joint movements without the apparatus disengaging from the user's foot during resistance exercises. The elastic cord is

2

surrounded by a fabric of greater elasticity to protect the user in the event the elastic cord snaps during use, the elastic cord is selected from the group comprising polyvinyl chloride tubing, thermoplastic polyurethane tubing, bungee cord.

BRIEF DESCRIPTION OF THE FIGURES

The detailed description of some embodiments of the invention will be made below with reference to the accompanying figures, wherein like numerals represent corresponding parts of the figures.

FIG. 1 shows a schematic perspective view of one embodiment of the present invention;

FIG. 2 shows a front view of one embodiment of the invention;

FIG. 3 is a section detail view of one embodiment of the invention along line 3-3 in FIG. 1.

FIG. 4 is a section detail view of one embodiment of the invention along line 4-4 in FIG. 3.

FIG. 5 is a side view of one embodiment of the invention in exemplary usage.

FIG. 6 is a perspective view of one embodiment of the invention in exemplary usage.

FIG. 7 is a detail perspective view of the invention shown in exemplary usage.

DETAILED DESCRIPTION OF CERTAIN EMBODIMENTS

By way of example, and referring to FIGS. 1 through 7, one embodiment of the present apparatus 10 comprises an elastic cord 20 with a first end and second end forming a primary loop 12 at each end. Primary loop 12 is configured to engage the dorsum and plantar surfaces of a user's 24 foot. The primary loop 12 may be formed using mechanical means such as clamps 16 or other means readily known to persons of ordinary skill in the art. It is preferred that when clamps 16 are used to form the primary loop 12 that spacers 22 are placed between each clamp 16 as depicted in FIG. 3.

An auxiliary loop 14 is connected to primary loop 12 as depicted in FIGS. 3 and 4 using mechanical means such as clamps 16 or other means readily known to persons of ordinary skill in the art. It is preferred that when clamps 16 are used to connect the auxiliary loop 14 to the primary loop 12 that spacers 22 are placed between each clamp 16 as depicted in FIG. 3. Clamps 16 can be covered with covering 26. The auxiliary loop 14 is configured to engage the calcaneus bone of the user 24 when primary loop 12 engages the dorsum and plantar surfaces of the user's foot centering the apparatus at the talocrural joint to enable the user to perform talocrural joint movements without the apparatus disengaging from the user's foot during resistance exercise as depicted in FIGS. 5 and 7.

Alternatively, as depicted in FIG. 6, the primary loop 12 and auxiliary loop 14 may be gripped by the user 24 in his hands to perform arm exercises using the apparatus 10. Further, as depicted in FIG. 5 one primary loop 12 and auxiliary loop 14 may be gripped by the user 24 in his hands and the second primary loop may be secured to the user's 24 foot in order to perform full body exercises.

The elastic cord 20 may be fabricated from polyvinyl chloride tubing, thermoplastic polyurethane tubing, bungee cord, or any other elastic cord. A sheath 18 having an elasticity greater than the elastic cord 20 surrounds the elastic cord 20. The inclusion of a sheath 18 reduces the risk of injury to the user if the elastic cord 20 snaps or breaks

3

during use, especially during functional movements, flexibility and stretching exercises.

Persons of ordinary skill in the art may appreciate that numerous design configurations may be possible to enjoy the functional benefits of the inventive systems. Thus, given the wide variety of configurations and arrangements of embodiments of the present invention the scope of the invention is reflected by the breadth of the claims below rather than narrowed by the embodiments described above.

What is claimed is:

1. An elastic resistance training apparatus for the performance of ankle plantar flexor resistance exercises, dorsi flexor resistance exercises, ankle inverter resistance exercises, or ankle everter exercises by a user, the apparatus comprising:

an elastic cord with a first end attached to a first primary loop and a second end attached to a second primary loop wherein the first primary loop and the second primary loop are configured to engage the dorsum and plantar surfaces of the user's foot;

a first auxiliary loop, wrapped around the first primary loop at two first primary loop points and a second auxiliary loop wrapped around the second primary loop at two second primary loop points, directly attached to the second primary loop wherein the first auxiliary loop and the second auxiliary loop are configured to engage the user's calcaneus bone when the primary loop engages the dorsum and plantar surfaces of the user's foot centering the apparatus at the talocrural joint to enable the user to perform talocrural joint movements without the apparatus disengaging from the user's foot during resistance exercises; wherein the first primary loop, the second primary loop, the first auxiliary loop and the second auxiliary loop are made from an elastic resistance tubing.

2. The elastic resistance training apparatus of claim 1, wherein the elastic cord is surrounded by a fabric of greater elasticity to protect the user in the event the elastic cord snaps during use.

4

3. The elastic resistance training apparatus of claim 1, wherein the elastic resistance tubing is selected from the group consisting of polyvinyl chloride tubing, thermoplastic polyurethane tubing, and bungee cord.

4. An elastic resistance training apparatus for the performance of ankle plantar flexor resistance exercises, dorsi flexor resistance exercises, ankle inverter resistance exercises, or ankle everter exercises by a user, the apparatus comprising:

an elastic cord with a first end attached to a first primary loop and a second end attached to a second primary loop wherein the first primary loop and the second primary loop are configured to engage the dorsum and plantar surfaces of the user's foot;

a first auxiliary loop, wrapped around the first primary loop at two first primary loop points and a second auxiliary loop wrapped around the second primary loop at two second primary loop points, directly attached to the second primary loop wherein the first auxiliary loop and the second auxiliary loop are configured to engage the user's calcaneus bone when the primary loop engages the dorsum and plantar surfaces of the user's foot centering the apparatus at the talocrural joint to enable the user to perform talocrural joint movements without the apparatus disengaging from the user's foot during resistance exercises;

a first primary loop first clamp slid around the first primary loop fixing the first primary loop in a first primary loop position and flanked by a first primary loop first spacer and a first primary loop second spacer.

5. The elastic resistance training apparatus of claim 4, further comprising a first primary loop second spacer slid around the first primary loop and flanked by the first primary loop second spacer and a first primary loop third spacer.

6. The elastic resistance training apparatus of claim 5, further comprising a first primary loop covering, slid over the first primary loop first spacer, the first primary loop first clamp, the first primary loop second spacer, the first primary loop second spacer and the first primary loop third spacer.
